PUNCH PRESS AND THE LIKE

Kenneth E. Reese, Elkhart, Ind.

Application January 30, 1947, Serial No. 725,352

7 Claims. (Cl. 164—103)

1

This invention relates, in general, to punch presses, and has particular relation to a counteracting or counterbalancing mechanism and improved leg structure or base frame for punch presses of the type that have a tilting frame pivoted on the leg structure or base frame.

While I have referred to the invention as useful for punch presses and shall hereinafter in connection with the drawings describe the invention in that regard, it is to be understood that the counteracting or counterbalancing mechanism and leg structure or base frame of the present invention may be employed for all similar purposes within the scope of the broader aspects of the present invention.

In prior devices of the sort to which the present invention particularly appertains, tilting of the tilting or pivoted frame about its pivotal support on the main base frame has been accomplished only with difficulty and danger to the operator. Worm and rack mechanisms, hydraulic cylinders and pistons, and other forms of inclining mechanisms have been required to incline or tilt the tilting frame about its pivotal support on the main base frame. These mechanisms have made the press complicated and expensive, and operators thereof have been seriously injured or killed, for example, where a worm slipped out of engagement with its cooperating rack.

One of the main objects of the present invention is to provide a counteracting or counterbalancing mechanism for the tilting or pivoted frame of apparatus of the class described which will facilitate tilting or inclining of the pivoted frame and eliminate the possibility of injury to the operator in inclining or tilting the frame to its different positions.

Another object of the invention is to provide an improved leg or base frame structure; also a new and advantageous combination of the counteracting or counterbalancing mechanism with the leg or base frame structure.

Another object of the invention is to provide a counteracting or counterbalancing mechanism and an improved leg or base frame structure with which the worm and rack, hydraulic cylinders and pistons and other forms of inclining mechanisms heretofore required may be eliminated.

Another object of the invention is to provide a counteracting or counterbalancing mechanism and an improved leg or base frame structure having various features of novelty and various advantages and which are particularly characterized by their simplicity in construction, their relatively few parts, their economy in manufacture and their ease and effectiveness in use.

2

Further objects and advantages of the invention will be apparent from the following detailed description, taken in connection with the accompanying drawings in which:

5 Figure 1 is a side elevational view of a punch press embodying the present invention, showing the tilting frame in vertical position in full lines and in one of its inclined positions in dotted lines;

10 Figure 2 is a rear elevational view of the punch press shown in Figure 1;

Figure 3 is an enlarged fragmentary side elevational view showing in detail the pivotal mounting of the tilting frame on the main base frame, suitable means for locking the tilting frame in its various inclined positions and the upper portion of the counteracting or counterbalancing mechanism;

15 Figure 4 is a fragmentary horizontal detail section taken on the line 4—4 of Figure 1;

Figure 5 is a fragmentary detail section taken on the line 5—5 of Figure 3;

20 Figure 6 is a fragmentary detail section taken on the line 6—6 of Figure 3; and

25 Figure 7 is a fragmentary detail section taken on the line 7—7 of Figure 1.

20 Referring now to the drawings, the punch press selected for illustration comprises a main base frame 1 having opposite legs or sides 2, 2 and a tilting frame 3.

25 The frame 3 has, for example, opposite sides 4, 4 pivoted at 5, 5 to the opposite legs or sides 2, 2, of the frame 1. The frame 3 has, for example, a bed 6 provided with a bolster plate 7. The sides 35 of the frame 3 may be connected, for example, by an integral connecting web 8, although this and the other features described in detail above may vary.

30 The crank shaft 9 is suitably journaled in the upper forwardly overhanging ends of the sides of the frame 3. The shaft 9 has, for example, an eccentric (not shown) which actuates a pitman 10 to impart reciprocatory movement to the ram or holder 11 which carries the punch or other tool 40 employed by the press. The rotating power member may be in the form of a flywheel 12 mounted on the crank shaft 9. The flywheel 12 may be driven by a suitable belt, or the shaft 9 may be driven otherwise as desired.

45 Each side or leg 2 of the base frame 1 is preferably in the form of a unitary casting having a horizontal portion 13 near its lower end, and integral upwardly converging arms 14 connected at the top at 15. The bottom of each leg 2 has 50 feet 16 adapted to rest on the floor indicated at 17. Tilting movement or angular adjustment

of the frame 3 about the pivot 5 is permitted by arcuate slots 18 in the upper portions of the legs 2 through which threaded pins 19 on the tilting frame 3 extend. Nuts 20, screwed on the outer ends of the pins 19 are adapted, when tightened, to lock the frame 3 in any desired tilted or adjusted angular position in the conventional manner. The legs 2 may be connected or tied together if and as desired.

Extending diagonally and formed integral with each leg 2 is a cored or tubular section 21, the outer surface of which may be flush with the outer surface of the leg. The inner surfaces of the upper portions 15 of the legs 2 have integral rounded flanges 22 which form, as continuations of the hollow interiors of the tubular sections 21, channels 22' which are curved upwardly to the upper ends of the legs 2.

A coiled compression spring 23 is positioned within each tubular section 21 and extends upwardly within the channels 22'. Operating slidably within each channel 22' and cooperating with the upper ends of the springs 23 are plugs 24. Each plug 24 has a part 25 which extends through and operates slidably in a slot 26 between the inner ends of the flanges 22 or in the inner sides of the tubular spring channels. The inwardly extending parts 25 of the plugs 24 are secured to the adjacent sides of the frame 3, for example, by screws or bolts 26 or other fastening means. If desired, the parts 25 may, within the scope of the present invention, be formed integral with the frame 3.

The lower ends of the tubular sections 21 may have externally accessible screws 27 threaded therethrough and provided with internal abutments abutting the lower ends of the springs 23. By the simple expedient of turning these screws 27, the counteracting or counterbalancing action of the springs 23 may be adjusted as desired.

The upper or outer end of each channel 22' is provided with a cap plate 28 fastened to the upper end of the legs 2 by screws or bolts 29. The plugs 24 are disposed beneath the cap plates 28 so that these plates act as stops for limiting outward movement of the plugs 24, and thereby angular movement of the frame 3 in a counterclockwise direction about the pivots 5.

In operation, the springs 23 act to counteract or counterbalance the weight of the tilting frame 3 whenever the nuts 20 are released to permit tilting or inclining this frame. With the nuts 20 or other locking means released, the frame 3 may be tilted or inclined in a clockwise direction from its vertical position shown in full lines in Figure 1, by exerting just enough force to overcome the action of the springs 23.

The springs 23 hold the frame 3 in vertical position when the locking nuts 20 are released. They not only eliminate hazards to the operator in tilting the frame 3 to different angular positions, but they also eliminate the necessity for worm and rack, hydraulic cylinders and pistons, and other forms of inclining mechanisms heretofore required. When the nuts 20 are released and the frame 3 is swung in a clockwise direction about the pivots 5 and locked in such position by tightening the nuts 20, the springs 23 are compressed. When the nuts 20 are again released the springs 23 may act to return the frame 3 to vertical position. As already pointed out, in adjusting the frame 3 to different angular positions, only sufficient force to overcome the counteracting or counterbalancing action of the springs 23 is required. Angular adjustment is therefore ac-

complished easily and without danger of injury to the operator.

The embodiment of the invention shown in the drawings is for illustrative purposes only, and it is to be expressly understood that such drawings and the accompanying specification are not to be construed as a definition of the limits or scope of the invention, reference being had to the appended claims for that purpose.

10 I claim:

1. In apparatus of the class described, in combination, a main base frame, a tilting frame pivoted on said base frame for inclining movement to different angular positions, a spring channel in said base frame, a plug slidable in said channel and having a part which extends through and operates slidably in a slot in the wall of said channel and is connected to the tilting frame, a coiled compression spring disposed in said channel and acting against said plug, and a cap plate fastened to said base frame and closing the adjacent end of said channel outwardly of said plug whereby to form a stop for limiting outward movement of the plug and thereby angular movement of the tilting frame.

2. In apparatus of the class described, in combination, a main base frame, a tilting frame pivoted on said base frame for inclining movement to different angular positions, a spring channel in said base frame, a plug slidable in said channel and having a part which extends through and operates slidably in a slot in the wall of said channel and is connected to the tilting frame,

30 3. In apparatus of the class described, in combination, a main base frame, a tilting frame pivoted on said base frame for inclining movement to different angular positions, a spring channel in said base frame, a plug slidable in said channel and having a part which extends through and operates slidably in a slot in the wall of said channel and is connected to the tilting frame, a coiled compression spring disposed in said channel and acting against said plug, a cap plate fastened to said base frame and closing the adjacent end of said channel outwardly of said plug whereby to form a stop for limiting outward movement of the plug and thereby angular movement of the tilting frame, and means adjacent to the opposite end of said spring for adjusting said spring and thereby its counteraction to the weight of the tilting frame.

40 4. Apparatus according to claim 1 wherein the spring channel and the spring therein are disposed diagonally of said base frame with their upper portions curved upwardly to the top of said frame.

45 5. A leg structure for a punch press having a spring channel as an integral part thereof, a plug slidable in said channel and having a part which extends through and operates slidably in a slot in the wall of said channel for connection with a tilting frame, a coiled compression spring disposed in said channel and acting against said plug, and a cap plate fastened to said leg structure and closing the adjacent end of said channel outwardly of said plug whereby to form a stop for limiting outward movement of the plug.

60 6. A leg structure according to claim 4 wherein the spring channel and the spring therein are disposed diagonally of the leg structure with their upper portions curved upwardly to the top of said leg structure.

65 7. In apparatus of the class described, in combination, a main base frame, a tilting frame pivoted on said base frame for inclining movement to different angular positions, a spring channel in said base frame, a plug slidable in said channel, a coiled compression spring disposed within said channel and acting against said plug, and means connecting said plug to said tilting frame whereby the action of said spring against said plug counteracts the weight of said tilting frame, the spring channel having a curved por-

tion concentric with the pivot between the tilting frame and the base frame.

7. In apparatus of the class described, in combination, a main upright base frame having arcuate slot means, a tilting frame having normally upright position and pivoted to the base frame for swinging movement about a generally horizontal axis to different angular positions, threaded pin means on the tilting frame extending through the arcuate slot means on the base frame and movable in said slot means with swinging movement of said tilting frame, nut means screwed on said threaded pin means and adapted, when tightened, to lock the tilting frame in any angular position to which it may be tilted, and balancing means disposed diagonally of said base frame with the upper portion thereof curved toward cooperation with said tilting frame for balancing the entire weight of said tilting frame whereby when said nut means is released said tilting frame may be tilted from its normally up-

right position to different tilted positions by exerting just enough force to overcome the action of said balancing means.
